UNITED STATES PATENT OFFICE.

WALTER DWIRE CHAPPUIS, OF SANTA ANA, CALIFORNIA.

PUMP-ROD SUSPENSION DEVICE.

Application filed August 27, 1924. Serial No. 734,442.

To all whom it may concern:

Be it known that I, WALTER DWIRE CHAPPUIS, a citizen of the United States, residing at Santa Ana, in the county of Orange 5 and State of California, have invented new and useful Improvements in Pump-Rod Suspension Devices, of which the following is a specification.

This invention relates more specifically to 10 a device for automatically engaging and suspending within an oil well derrick, sections of well pump sucker rods as the sectional rod is withdrawn from the well.

It is a primary object of my invention to 15 provide a simple rod suspension device consisting of a single casting and provided with flexible suspension means, whereby pump rod sections may be quickly and easily suspended from a supporting structure adjacent 20 the pump as they are withdrawn from the pump, and may be readily removed from the device when the sections are replaced.

A further object is to provide a device 25 consisting of a single casting, that requires no machining to render it marketable or usable, and which will securely hold rod sections in a suspended position until they are again required.

In the accompanying drawings I have 30 illustrated a preferred embodiment of my invention, it being understood however, that no limitation is necessarily made to the precise structural details therein exhibited, but various changes, alterations, and modifications 35 may be resorted to within the scope of my invention when desired.

Fig. 1 is a front elevation of the rod suspension device showing the upper end of a rod section engaged therein and the rod elevator in engagement therewith.

Fig. 2 is a longitudinal section of the device taken on line 2—2 of Fig. 1.

Fig. 3 is a front view of the device showing the method of engaging a rod section.

Fig. 4 is a top plan view of the device with a rod section in place thereon.

In pumping oil from wells, and particularly where the pumps are located at great depths, sectional pump sucker rods are employed, each section being about thirty feet long, the sections being coupled together to form a rigidly unitary rod extending from the pump to the upper end of the well. When it is desired to remove the pump for repacking, or any other cause, the sucker rod is uncoupled at every third section as

the same is withdrawn, and the sections are placed along side of the well derrick or stacked in a convenient position within the derrick. Much valuable time is wasted in 60 reassembling the rod sections when the pump is replaced within the well owing to stacked condition of the rod sections and the consequent difficulty of moving the same into a convenient position for coupling.

By means of my improved suspension device, as the rod sections are conveniently suspended within the derrick frame, they can be readily moved into position for reassembling with little or no difficulty.

Referring more particularly to the accompanying drawings, the improved rod suspension device preferably consists of a single metal casting 5, preferably consisting of a straight shank portion 6, having a cone shaped head 7 provided with a downwardly extending socket 8, enlarged at its lower end, and opening at its bottom into a boss 9 formed on the front wall of the shank, the socket providing a convenient means for 80 readily attaching the wire suspension cable 10 thereto. In securing the suspending cable in the socket 8, its upper end is first inserted upwardly through the bottom of the socket 8, the cable wires at its lower end are then unstranded and a Babbitt metal is poured into the enlarged lower portion of the socket 8 to securely fasten the cable to the head 7 of the rod suspension device. The free end of the cable (not shown) may be 85 provided with a hook, or ring so that it may be readily secured to the framework of the derrick or other supporting means.

From the lower end of the straight shank portion 6 the body extends downwardly in 90 the form of a pair of arms 11, 12, the upper portions 13 of each arm being segmental and forming a substantially circular opening, whose diameter is slightly greater than the diameter of the annular shoulder 14 formed 100 adjacent the upper end of a pump rod section in order to permit of its ready passage therethrough. The lower vertically disposed portions 15, 16, extend downwardly a short distance from the segmental portions 105 13 and in parallel relation, the width between the oppositely disposed surfaces of portions 15, 16, being slightly greater than the wrench hold 17 formed on the rod sections directly below the annular shoulder 14. The 110 lower ends of the vertical portions 15, 16, are turned outwardly a short distance at

substantially right angles thereto as at 19, 20, to form a support for a rod section when suspended therein, the annular shoulder 14 resting thereon as clearly shown in the various figures of the drawing. The ends of portions 19, 20, are connected by a rod retaining bar 21, designed to prevent an accidental disengagement of a rod section when suspended from the device.

10 The operation of the rod suspension device will be clearly apparent from the following. The rod suspension devices as heretofore noted are secured by means of flexible cables in the upper portion of the derrick frame-
15 work, and at a height sufficient to permit of the suspension of three sections of a pump rod (about 90 feet). A workman is stationed in the upper portion of the derrick to manipulate the suspension devices to secure
20 the rod section thereto as the same are withdrawn from the well by means of the well known rod elevator 25, which engages the upper end of the rod 26 just below the annular shoulder 27 formed at the base of the
25 squared wrench hold. The extreme upper end 28 of the rod is threaded for engagement with the threaded socketed end of another rod section (not shown). As the pump (not shown) is withdrawn from the well a stand
30 of pump rods consisting of three sections, is uncoupled, the workman in the derrick top inserts the upper end of the stand through the circular opening formed in the rod sus-
35 pension device, the device being turned from its vertical to a horizontal position in the manner shown in Fig. 3, until the annular shoulder 14 passes therethrough. The device is then returned to its normal vertical position, the annular shoulder 14 engaging
40 the end portions 19, 20, and bar 21, thus detachably supporting the stand of pump rods in a suspended position within the derrick structure. The above operation is continued
45 until all the rod sections are suspended in position.

When the pump has been repaired the workman again takes his place in the derrick and releases the sections one after another from the suspension devices as they are coupled together.

By the construction above described it will be obvious that it will be absolutely impossible to disconnect a rod section from a suspension device except by turning the device

from its normal vertical suspended position 55 to a horizontal one as shown in Fig. 3. This feature is considered highly essential, for should the rod sections become accidentally disengaged from the suspension devices fatalities would often result to the workmen 60 on the derrick floor.

It will be apparent that I have provided an extremely simple rod suspension device, and one that may be readily and economically manufactured, no machine work being 65 required as the casting can be formed sufficiently smooth to meet all requirements.

What I claim is:

1. A rod suspension device comprising a cast body member consisting of a shank portion the lower end of said shank having a pair of segmental arms extending downwardly therefrom and forming a substantially circular opening, the ends of said arms extending below the segmental portions disposed in parallel relation and spaced apart, the distance between the parallel portions being less than the distance between the segmental portions, whereby to permit the passage therethrough of circular flanges, the 70 extreme ends of the arms extending outwardly from the parallel end portions and substantially at right angles thereto to form a rod supporting seat, and a cross bar connecting the ends of the right angled portions. 75

2. A device of the class described comprising a shank portion having a cable attaching means formed on its upper end, the lower end of the shank including a pair of 80 downwardly extending arm portions, the upper portions being circularly formed to permit of the free passage of annular rod flanges therethrough, said arms below the circular portions extending downwardly in parallel relation, the distance between the parallel arm portions being less than the diameter of the circular opening thereabove, the extreme ends being turned at substantially right angles to the parallel portions 95 to form a rod supporting seat, and a cross bar connecting the extreme ends of the right angled portions. 100

In witness that I claim the foregoing I have hereunto subscribed my name this 31st 105 day of July, 1924.

WALTER DWIRE CHAPPUIS.
